(57) **CLAIM**

I claim the ornamental design for the bottle, as shown and described.

DESCRIPTION

FIG. 1 is a bottom view of the new ornamental bottle of the present invention.

FIG. 2 is a right side view thereof, the left side being a mirror image thereof.

FIG. 3 is a side perspective view thereof.

FIG. 4 is a top view thereof.

FIG. 5 is a bottom view of a bottle according to a second embodiment.

FIG. 6 is a right side view thereof, the left side being a mirror image thereof.

FIG. 7 is a side perspective view thereof.

FIG. 8 is a top view thereof.

FIG. 9 is a bottom view of a bottle according to a third embodiment.

FIG. 10 is a right side view thereof, the left side being a mirror image thereof.

FIG. 11 is a side perspective view thereof.

FIG. 12 is a top view thereof.

FIG. 13 is a bottom view of a bottle according to a fourth embodiment.

FIG. 14 is a right side view thereof, the left side being a mirror image thereof.

FIG. 15 is a side perspective view thereof; and,

FIG. 16 is a top view thereof.

The broken line showing portions of a bottle forms no part of the claimed design.

1 Claim, 4 Drawing Sheets
